OFFSET PRINTING PRESS

Herman Gould, Brooklyn, and Frank Ackerman,
New York, N. Y.

Application October 7, 1935, Serial No. 43,906

4 Claims. (Cl. 101—35)

The present invention relates to a means for and the method of printing upon or ornamenting objects of various kinds and aims to provide certain improvements therein. More particularly it 5 relates to the art of applying by a transfer method from rigid type, dies, electrotypes, etc., printed matter, decorations, designs, monograms, emblems, insignia and the like upon plane or curved surfaces of rigid or somewhat deformable articles 10 or objects regardless of the material of which such objects are made.

The primary object of our invention is to provide a simple and economical means and method 15 of printing upon or ornamenting objects having curved or non-planar, rigid or somewhat deformable surfaces, for example, articles of glassware, china, vanity cases, umbrella handles, rubber balls and the like. A further object is to provide a device of the character specified wherein the type, 20 die, electrotype or the like containing the matter to be imprinted can be readily removed from and replaced in the device so that a single impression may be transferred to an article or as many of the same or different impressions as desired may 25 be applied to a plurality of similar or different articles. A further object is to provide a portable device of the character specified wherein the transfer element in its operative transferring position is disposed in a manner to facilitate the 30 transfer of the matter to be printed to the articles where such articles are relatively small and can be easily brought into cooperative relation with the transfer means; also where said transfer means is readily bodily removable from the device 35 to permit the transfer or application of the desired matter to objects which cannot be conveniently brought into cooperative relation with the transfer means.

The foregoing and other objects of our invention 40 not specifically mentioned we accomplish by modifying any ordinary portable or stationary printing press by substituting or applying to the platen frame thereof a transfer pad composed of suitable elastic material such as gelatin, rubber 45 and the like having a surface adapted to take an ink or ink base impression from type, dies, electrotypes, etc., and to transfer said ink impression to an article when the pad and the article are brought into proper contacting relation. 50 In other words, our invention resides in a sense in converting an ordinary printing press into an offset printing press wherein the offset transfer pad after each inking is brought to rest in a preferably substantially horizontal position to facilitate 55 application thereto of the article onto which

the impression is to be transferred. We also preferably mount the transfer pad so as to be readily removable from and replaceable in the platen frame to permit the manual application of the transfer pad onto the article which is to receive 5 the matter to be imprinted and which cannot conveniently be applied to the transfer pad. The invention will be better understood from the detailed description which follows when considered in conjunction with the accompanying drawing, 10 wherein:

Figure 1 is a perspective view of a portable printing press embodying our invention.

Fig. 2 is an enlarged top plan view of the platen frame and transfer pad when disposed in substantially horizontal position.

Fig. 3 is a side elevation of the platen frame and transfer pad shown in Fig. 2 and its cooperative connections with other parts of the press.

Fig. 4 is a top plan view of the transfer pad 20 and its support removed from the platen frame.

Fig. 5 is a view showing the manner of applying the transfer pad, after its removal from the press, to an article upon which the matter to be printed is to be transferred.

Referring first to Figs. 1 to 3 of the drawing, the portable printing press disclosed therein may be of any type and as shown comprises a base 10 having mounted thereon a block 11 having a pair of upstanding ears 12 through which extend 30 a pivot pin 13. Also mounted on the base 10 is a substantially vertical frame 14 adapted to support on its front face printing means 15 which may be in the nature of type, dies, electrotype or the like held within a suitable chase 16. Supported by the frame 14 is an inking disk 17 adapted to supply ink to a pair of inking rolls 18 which are supported by a pair of carriers 19 (only one of which is shown) which are pivotally mounted as at 20 to move the inking rolls over the disk 17 40 to take up ink therefrom and then down over a pair of rails 21 on the front of the frame 14 to apply said ink over the surface of the printing means 15 mounted in the frame.

Pivots mounted on the pin 13 is a platen 45 frame 22 having an operating handle 23 and an open boxlike socket 22a defined by pairs of parallel walls 22b and 22c. Mounted within the platen frame socket 22a is an elastic transfer pad 24 formed of gelatin, rubber or other elastic material having a top surface adapted to receive an ink impression from the printing means 15 when brought into contact therewith.

The transfer pad 24 is mounted in and projects above the top of a rigid support 24a which at its 55

opposite ends is provided with outwardly extending alined pins 25 which terminate in engaging handles 26. The lateral side walls 22b of the platen frame socket are each formed with a bayonet slot 27 having a horizontal component and a vertical component which latter extends to the top of said walls for accommodating the pins 25 of the transfer pad support. Preferably the transfer pad support is formed of a width to snugly fit between the lateral walls 22b of the platen frame socket and of a length somewhat less than the length of said lateral walls and said support is adapted to be held in place within said platen frame socket by the pins 25 engaging and being held in the ends of the horizontal components of said bayonet slots by a tension leaf spring 28 or the like mounted for flexing action against the rear wall 22c of the platen frame socket. It will thus be seen that by compressing the spring 28 by the transfer pad support 24a, the latter can be quickly inserted into and removed from the platen frame socket.

Pivotedly connected to both the platen frame forwardly of the pivot pin 13 and the rolls carriers 19 forwardly of the pivot pin 20 are a pair of links 30 which when the platen is moved out of and into engagement with the printing means 15 moves the inking rolls 18 over the inking disk and over the surface of said printing means respectively to apply ink from said inking disk to said printing means. For limiting the degree of engagement of the transfer pad with the printing means 15 so as to insure a proper impression being obtained on the transfer pad 24 from the printing means, the platen frame is provided with adjustable screws 31 at one end thereof for contacting with the rails 21 of the frame 14.

In the operation of the device, positive face printing means 15 are mounted in the chase 16 within the frame 14, the transfer pad 24 is mounted in the platen frame socket 22a and the adjusting screws 31 are set to obtain a proper negative impression on the transfer pad from the printing means 15. As herein shown the printing means is in the form of a die bearing the letter G within a circle. The disk 17 carries ink or an ink base which, as the platen frame is moved about its pivot causes the inking rolls 18 to take ink from the disk and apply it over the surface of the die 15. When the die is properly inked a negative impression therefrom will be obtained on the surface of the transfer pad 24 as shown in Fig. 2 upon moving the transfer pad into and out of engagement with the die. Where it is desired to transfer this impression to a small object, such object may be pressed into engagement with the inked negative impression on the pad 24 to receive a positive impression thereof while the transfer pad is in its substantially horizontal or rest position. If the article has a round or spherical surface, for example, a salt cellar with a conical wall as shown in dotted lines in Fig. 2, it may be rolled into contact with the surface of the pad 24 which being elastic will yield so as to transfer the impression to such curved surface. Preferably the inking composition employed should have a base which will adhere to any smooth surface and serve as an adhesive for a metallic powder which may be dusted thereover where a metallic ornamentation is desired. In such case the excess powder may be brushed away after the inked base is dry and the retained powder which will correspond with the design or lettering impressed upon the article may then be painted over with a transparent water-proof lac-

quer to insure its permanency on the article. Where it is desired to apply the design upon an article which cannot be brought into engagement with the transfer pad, the transfer pad may be quickly bodily removed from the platen frame by grasping the handles 26 and moving the transfer pad support against the tension of the spring 28 to release the pins 25 of the pad support from the bayonet slots in the platen frame socket, whereupon said transfer pad may be pressed into engagement with the desired object in the manner shown in Fig. 5. The same procedure with regard to dusting with metallic powder and finishing as outlined above may then be followed.

Where a given design or ornamentation is to be imprinted upon a plurality of objects it is apparent that an impression on the pad 24 can be obtained each time the platen is moved into engagement with the die and such impression then transferred to the article. Where but a single impression of a given character or design is desired, the type or die can be readily removed from the press frame and another quickly substituted in its place. It will thus be appreciated that the invention herein disclosed readily lends itself to application for either special short order or repetition work and is particularly suitable for use in department stores where articles of various shapes and character such as china ware, glass-ware, umbrella handles, vanity cases, smoking pipes and the like can be monogrammed or otherwise ornamented in a facile and economical manner.

From the foregoing detailed description it will be understood that while we have shown and described but two general applications of our invention and but a single mechanism for carrying out the same, we do not wish to be limited to any specific use of our method or to any particular construction of machine for practicing the same since these have general application and can be readily adapted to existing types of printing machines without departing from the spirit of the invention as claimed.

What we claim is:

1. A machine of the character described comprising a flat printing plate having readily changeable printing means, a platen frame having an elastic transfer pad with a substantially flat transfer surface adapted to receive an ink impression from the printing means, said transfer pad being mounted in a support which is removably held by the platen frame and cooperating means on the platen frame and the transfer pad support for normally holding said parts in assembled relation, said means being quickly engageable and disengageable for facilitating the application of the transfer pad to and its removal from the platen frame.

2. A machine of the character described comprising printing means, a platen frame having an elastic transfer pad adapted to receive an ink impression from the printing means, said transfer pad being mounted in a support which is removably held by the platen frame, a pin and bayonet slot connection between the platen frame and the transfer pad support and said transfer pad support having hand engaging portions for facilitating the quick application of the transfer pad to and its removal from the platen frame.

3. A machine of the character described comprising printing means, a platen frame having an elastic transfer pad adapted to receive an ink impression from the printing means, said transfer pad being mounted in a support which is re-

45

movably held by the platen frame, the platen frame having bayonet slots in its side walls, the transfer pad support having laterally extending pins for engaging in said slots and said pins terminating in hand engaging portions for facilitating the quick application and removal of the transfer pad from the platen frame.

5. A machine of the character described comprising printing means, a platen frame, an elastic transfer pad adapted to receive an impression from the printing means, said platen frame hav-

ing a socket and said transfer pad being mounted in a support which is removably held in the socket of the platen frame, a pin and slot connection between the platen frame and the transfer pad support for facilitating the quick application and removal of the transfer pad from the platen and spring means cooperating with the pin and slot connection for holding the transfer pad support within the platen frame in assembled relation.
